UNITED STATES PATENT OFFICE.

CHARLES W. STEELE, OF AKRON, OHIO; ASSIGNEE TO THE MILLER RUBBER COMPANY,
OF AKRON, OHIO.

BALL-VARNISHING MACHINE.

Application filed October 30, 1922. Serial No. 597,983.

To all whom it may concern:

Be it known that I, CHARLES W. STEELE, a citizen of the United States, and resident of Akron, in the county of Summit and 5 State of Ohio, have invented certain new and useful Improvements in Ball-Varnishing Machines, of which the following is a specification.

My present invention relates to improvements in coating or varnishing machines, and concerns more particularly a machine for applying a coating of varnish or similar material, to the surfaces of rubber playing balls, though not limited to this specific use.

These balls are manufactured in exceedingly large quantities and heretofore, so far as I am aware, it has generally been customary to apply the coatings by dipping, 20 coating by hand being too tedious and expensive. The dipping process has been found unsatisfactory, however, in that the presence of minute quantities of greasy material in the surface of the ball so destroys 25 the surface tension of the applied film that relatively large areas will remain uncoated, and further that excess of coating material causes trouble by collecting on the lower side of the ball.

The present invention aims to provide a machine which will be free from these objections, which will apply only the requisite amount of coating material to the balls, and this smoothly and evenly, and which 35 will perform such action in a rapid and economical manner.

With these and other objects in view, the invention includes the novel features of construction and arrangement and combination of parts hereinafter described, the nature and scope of my invention being particularly defined by the appended claims.

A machine constructed in accordance 45 with my invention is illustrated in the accompanying drawings, in which:

Figure 1 is a side elevation of a ball varnishing or coating machine.

Fig. 2 is an end elevation (delivery end).

Fig. 3 is a transverse sectional view 50 through the drum.

Fig. 4 is a longitudinal section partly broken away, and

Figs. 5, 6 and 7 are detail views.

Referring by reference characters to these 55 drawings, the numeral 1 indicates a rotat-

able cylindrical drum provided with annular rails 2 which rest upon cradle rollers 3 driven through suitable gearing 4 from any convenient source of power, such as an electric motor indicated conventionally at 5. The drum 1 is provided at each end with an annular head or cover 6, that at the delivery end being provided with discharge openings 6^a large enough for a ball to roll therethrough. These openings are 60 produced by cutting annularly arranged horseshoes shaped openings in the cover and bending back the partially freed material. Two openings are shown in the drawing and more can be provided if desired, to allow the balls to emerge faster. 65

Between the ends of the drum one or more partitions similar to the delivery end cover may be provided, one being shown in the drawings as indicated at 7. This partition is provided with openings 7^a similar to openings 6^a. The purpose of the partition or partitions is to prevent the balls from travelling through the drum at too great a velocity. I have found one such 80 partition satisfactory, but more can be provided where necessary, or the same result can be accomplished by making openings 7^a less in number than openings 6^a.

Between each cover and the partition, and between partitions, where more than one is used, I provide a series of depending longitudinally disposed curtains or brushing members, each formed from a plurality of layers of cloth and suspended from the 85 walls of the drum. In the drawing four of these curtains 8 are provided between each end and the central partition. These curtains are suspended from, or connected to the drum at points ninety degrees apart and 90 are of a length (from attachment point to free edge) substantially equal to the diameter of the drum.

In the operation of the device, enough of the coating material is thrown into the 100 drum to saturate the curtains at the feed end and to nearly saturate those at the discharge end. Thereafter coating material is added to the feed end, sufficiently only to maintain these conditions. A quantity 105 of balls is then placed in the feed end and due to the drum being slightly inclined, they attempt to roll toward the other end. The rotation of the drum at a slow speed causes them to be dragged up the sides by 110

the contact of the depending curtains. In this way the balls become entangled or enfolded in the plurality of layers of curtains and receive a thorough brushing action as they proceed toward the opposite end of the drum. When they reach the central partition, they escape through the openings 7^a into the second section, where the same process is repeated.

10 When emerging from openings 6^a, the balls drop into a conveyor belt 9 running horizontally between side boards 10. Belt 9 is provided with a series of carriers 11 formed of sheet metal and provided each 15 with three equilaterally spaced contact points 11^a to support a ball. The plates are so placed on the belt that two of these points on one plate are equilaterally spaced with regard to a single point on the adjacent 20 plate. Side boards 10 are provided with sheet metal guide angles 12 to center the balls until they come to rest, and a plough 13 prevents the balls from piling upon each other. The conveyor is of sufficient length 25 to dry the balls, and delivers them in a suitable receptacle at the far end.

The curtains or brushing members, owing to the nature of the coating or varnishing material used, must be cleaned from time to 30 time to prevent their becoming coated with hardened varnish, and are therefore, made removable so that they can be taken out and treated or boiled with varnish solvent. A convenient manner of effecting such detachable connection is to secure the curtains in a removable manner to rods 14 by means of snap hooks 15 carried by the rods and engaging eyes 8^a in the curtains, these rods in turn being removably held by screw eyes 40 16 and 17 carried by the drum. Preferably the screw eye 17 adjacent the open end (inlet or discharge) is detachably held by a wing nut 17^a.

The interior of the drum is made smooth 45 to prevent injury to the balls, and also to facilitate cleaning.

Having thus described my invention, what I claim is:

1. A ball coating machine comprising a 50 rotatable drum having feed and discharge openings at opposite ends thereof, and a flexible fabric sheet having one edge secured to the inner wall of the drum lengthwise thereof.

55 2. A machine of the character described, comprising a rotating cylindrical drum having feed and discharge openings at opposite ends thereof, and a plurality of flexible

curtains of coating absorbent material having edges connected with the inner wall of 60 the drum in longitudinally spaced relation.

3. A machine of the character described, comprising a rotatable drum having inlet and discharge openings at opposite ends, and a plurality of flexible curtains of coating 65 absorbent material longitudinally disposed within the drum and carried thereby.

4. A machine of the character described, comprising a rotatable drum having inlet and discharge openings at opposite ends, and 70 a plurality of flexible curtains of coating absorbent material longitudinally disposed within the drum and carried thereby, each of said layers comprising a plurality of independent sheets of material connected with 75 the drum at one edge only.

5. A machine of the character described, comprising a rotatable cylindrical drum having inlet and discharge openings at opposite ends, partition means within the drum 80 dividing it into a plurality of cylindric chambers, said partition means having ball passages, and flexible wipers of absorbent material carried by the drum within each compartment.

6. A machine of the character described, comprising a rotatable cylindrical drum journaled on an inclined axis and having inlet and discharge openings at its opposite ends, and freely swingable flexible devices 90 saturated with coating material carried by said drum within the same.

7. A machine of the character described, comprising a rotatable cylindrical drum journaled on an inclined axis and having inlet and discharge openings at its opposite ends, and freely swingable flexible devices 95 saturated with coating material carried by said drum within the same, and means for retarding the passage of articles through 100 the drum.

8. A machine of the character described, comprising a rotatable cylindrical drum journaled on an inclined axis and having inlet and discharge openings at its opposite 105 ends, and freely swingable flexible devices saturated with coating material carried by said drum within the same, and means for retarding the passage of articles through the drum, said retarding means comprising a 110 partition member having one or more openings therein.

In testimony whereof, I affix my signature.

CHARLES W. STEELE.
